COIN CONTROLLING DEVICE FOR COIN
CONTROLLED VENDING MACHINESThomas W. B. Watling, Chicago, Ill., assignor to
Watling Manufacturing Company, Chicago, Ill.,
a corporation of Illinois

Application March 4, 1936, Serial No. 67,032

4 Claims. (Cl. 194—97)

This invention relates to the general art of coin controlled vending machines, and more especially to coin controlling devices by which an automatic selection of the means for actuating the coin controlled mechanism is effected, legitimate coins being accepted, and spurious substitutes being rejected. One of the commonest fraudulent coin substitutes used in these machines is a washer of substantially the thickness and diameter of the legitimate coin. Most of these washers are a standard product and easily obtainable on the market, and therefore are extensively used in efforts to cheat coin controlled vending machines.

15 The main object of this invention is to provide a very simple, inexpensive and efficient coin controlling device that may be relied on to pass proper and legitimate coins of the size for which the machine is intended and to reject washers and all similar articles that are formed with a central hole.

An illustrative embodiment of the invention is illustrated in the accompanying drawing, in which:—

25 Fig. 1 is a front elevation of the upper portion of a coin chute having my improved coin selecting device applied thereto.

Figs. 2, 3 and 4 are fragmentary vertical sections all taken on the line 2—2 of Fig. 1 and 30 showing the relative positions of the parts during the progress of a washer therethrough.

Fig. 5 is a view also on the line 2—2 of Fig. 1 showing the parts in the position corresponding to Fig. 3, but illustrating the action of the selector device on a legitimate coin.

Fig. 6 is a transverse section taken on the line 6—6 of Fig. 1.

Fig. 7 is an elevation similar to Fig. 1, viewed from the opposite side of the latter.

40 Figs. 8 and 9 are perspective details of the two members of an oscillating selector device, through the action of which legitimate coins are passed to the coin receptacle and washers or similar spurious tokens are thrown out. Referring to 45 the drawing, 10 and 11 designate as entireties two wall members that are connected as by screws 12 and are suitably spaced to form between them a coin chute 13. As shown in Fig. 1, the upper end of the wall 10 is cut away to provide an opening 14 of suitable size for the insertion sidewise into the chute of the coin.

In the wall 10, a short distance below the coin deposit opening 14 are upper and lower openings 15 and 16 respectively. Between these openings 55 and extending across the coin chute 13 is an in-

clined deflector ledge 17, said ledge separating the openings 15 and 16. Attached to the outer face of the wall 10 as by screws 18 are a pair of Z-bars 19, the adjacent inner portions of which overhang the side portions of the openings 15 and 16 and form between them a channel 20 that is laterally adjacent to the chute 13 and into which channel the tokens, whether a legitimate coin or a washer, are directed from the chute 13 by the deflector ledge 17, as is clearly shown in Fig. 2. 15 If the article deposited be a spurious annular token, such as a washer, it will fall through the channel 20, and drop onto the floor of the machine. If the deposited token be a legitimate coin of the size intended to be used on the machine, it will be pushed from the channel 20 back into the coin chute 13, will drop on an inclined ledge 21 conveniently formed integral with the wall 11 and extending through a slot 22 in the wall 10, and will roll down said ledge into a chute 23.

Coming now to a description of the selector device by which legitimate coins are accepted and washers and the like are rejected, mounted on one of the Z-bars 19 is an angle bracket 24, in 25 which is mounted a stud 25. Pivotally mounted on this stud are the two cooperating members of the coin selector shown in isolated detail in Figs. 8 and 9. Both of these members are flat metal members disposed side by side, and one of them 30 identified by 26 has a relatively longer finger 27, a notch 28 cut in its vertical edge above the finger 27, a counter weighted tail piece 29, and a stop lug 30 on its upper edge. The other member identified as a whole by 31 has a relatively short 35 finger 32, a tail piece 33, and a lateral lug 34 on the lower edge of the finger 32. When the parts are assembled on the stud 25, the lug 34 lies in and, in the operation of the device, plays between the top and bottom edges of, the notch 28.

As shown in Figs. 2 to 5 inclusive, the longer finger 27 is long enough to extend across the channel 20 and through the lower opening 16 into the chute 13. The shorter finger 32 is long enough to project into the channel 20, but does 45 not extend in any position thereof into the chute 13. The counter weighted tail piece 29 normally maintains the parts in the position shown in Fig. 2.

If a washer, identified by W is inserted into 50 the coin chute, it is handled by the selector device in the manner progressively illustrated in Figs. 2, 3 and 4. It is first deflected by the ledge 17 from the coin chute 13 into the channel 20. Its lower edge strikes the base of the finger 27 55

and thus rocks the member 26 through the position shown in Fig. 3 to the position shown in Fig. 4. And since the notch 28 is engaged with the lug 34 of the other member 31, the latter member 5 is rocked with the member 26. And since, as the washer falls down the channel, the end of the finger 32 enters the hole of the washer (Fig. 3) it does not interfere with the straight falling movement of the washer, so that the latter drops 10 out of the lower end of the channel, and in so doing its upper portion wipes across the upper corner of the finger 32 as shown in Fig. 4, thus swinging the member 31 slightly beyond or in excess of the swing of the member 26. This 15 excess movement is possible by reason of the fact that the lug 34 has a limited play between the top and bottom edges of the notch 28, and as a result of this excess play, the dropping washer is sufficiently far down in the channel before it 20 leaves contact with the finger 32 to avoid being caught and detained by the finger 27 on the return swing of the selector device.

On the other hand, when a legitimate coin such as C is deposited in the coin chute, it is first deflected by the ledge 17 into the channel 16, rocking the two members of the selector device to the mid position shown in Figs. 3 and 5, in which position the finger 32 strikes the center of the coin and pushes the latter off the finger 27 and 25 through the lower opening 16 into the coin chute 13, whence it rolls through the coin discharge chute 23 to and through the coin operated mechanism of the vending machine and thence to the proper coin receptacle.

35 To prevent the possibility of a washer, while sliding off the long finger 27 being accidentally directed into the coin chute, I provide a yieldable guard for the lower opening 16. This preferably takes the form of a plate 35 having on its upper end a pair of hinge lugs 36 (Fig. 7) pivoted on a pin 37 that is mounted on the rear side of the deflector ledge 17. A light torsion spring 38 encircling the pin 37 and at its opposite ends bearing on the ledge 17 and the back of the guard 40 plate 35 normally maintains the guard plate in the opening 16 as shown in Figs. 2, 3 and 4, and the spring 38 is strong enough to resist any tendency of the washer when sliding off the finger 27 to push the guard plate rearwardly. However, 45 when the end of the finger 32 strikes the coin C it acts through said coin to swing the guard plate inwardly, as shown in Fig. 5, so as to permit the coin to be delivered into the coin chute 13 under and during the final part of the coin selector device, the guard swinging back to normal position 50 as soon as the coin has passed.

The lug 30 on the member 26 is a stop device to prevent the selector device from spinning or 55 rotating on the stud 25, and this it does through contact with the top edge of the bracket 24.

On the upper portion of the coin chute is shown a hinged gate 39 pivoted on a rod 40 and normally closed by a spring 41, this gate covering an opening 42 in the chute wall 11. The purpose of this hinged gate is to permit the manual ejection of any bent coins or slugs which may become lodged in the neck of the chute. This device is fully shown and described in my former Patent 2,015,640, September 24, 1935, and since it 65 forms no part of the present invention, need not be herein further described.

It is believed that the foregoing description, in connection with the drawing, will make entirely clear to those skilled in the art, the man-

ner in which the device automatically accepts legitimate coins and rejects washers or other annular slugs. Manifestly, specific details of the structure may be varied within the purview and scope of the appended claims.

5

I claim:

1. A coin controlling device, comprising a gravitational coin chute and a coin channel laterally adjacent to said chute, a wall of said chute having an opening communicating with said channel, and an oscillatory selector device mounted opposite said channel and comprising two coaxially pivoted members each carrying a finger, one of said fingers normally lying across said channel and adapted to be struck and swung downwardly by a coin or washer, and the other finger adapted to enter the hole of a washer and thereby permit the latter to be discharged through said channel, and to engage a coin and push the latter through said opening into said chute, said members having cooperating means by which the swinging movements of one of said members are transmitted to the other member.

2. A coin controlling device, comprising a gravitational coin chute and a coin channel laterally adjacent to said chute, a wall of said chute having an opening communicating with said channel, and an oscillatory selector device mounted opposite said channel and comprising two coaxially pivoted members each carrying a finger, one of said fingers normally lying across said channel and adapted to be struck and swung downwardly by a coin or washer, and the other finger adapted to enter the hole of a washer and thereby permit the latter to be discharged through said channel, and to engage a coin and push the latter through said opening into said chute, said members having cooperating means comprising a notch in one of said members and a lug on the other member lying in said notch and having a limited play between the opposite edges of said notch, whereby the swinging movements of one of said members are transmitted to the other member and a limited relative swinging movement of said members is permitted.

25

3. A coin controlling device, comprising a gravitational coin chute and a coin channel laterally adjacent to said chute, a wall of said chute having an opening communicating with said channel, and an oscillatory selector device mounted opposite said channel and comprising two co-axially pivoted members one carrying a short finger and the other a long finger, said long finger normally lying across said channel and adapted to be struck and swung downwardly by a coin or washer, and said short finger adapted to enter the hole of a washer and thereby permit the latter to be discharged through said channel, and to engage a coin and push the latter through said opening into said chute, said members having cooperating means by which the swinging movements of one of said members are transmitted to the other member.

30

4. A coin controlling device, comprising a gravitational coin chute and a coin channel laterally adjacent to said chute, a wall of said chute having an opening communicating with said channel, and an oscillatory selector device mounted opposite said channel and comprising two co-axially pivoted members one carrying an upper short finger and the other a lower long finger, said long finger normally lying across said channel and adapted to be struck and swung downwardly by a coin or washer, and said short

finger adapted to enter the hole of a washer and thereby permit the latter to drop through said channel, and to engage a coin and push the latter through said opening into said chute, said members having cooperating means comprising a notch in one of said members and a lateral lug on the other member lying in said notch and

having a limited play between the opposite edges of said notch, whereby the swinging movements of one of said members are transmitted to the other member and a limited relative swinging movement of said members is permitted. 5
